FLUID PUMP

Ferdinand E. Fick, Lakewood, Ohio

Application January 30, 1933, Serial No. 654,156

8 Claims. (Cl. 103—173)

This invention relates to improvements in fluid displacement pumps and particularly to fluid pumps having a wobble plate for actuating pistons in cylinders.

5 Broadly the invention contemplates providing a wobble plate which is adapted to be rotated to drive pistons with means to automatically vary the angularity of the wobble plate to vary the stroke of the pistons.

10 In fluid pumps adapted for pumping fluids wherein the flow is controlled on the outlet side of the pump, it has been the usual practice to allow the pump to continue operation but to by-pass the fluid being pumped in order to prevent the fluid pressure from rupturing the conduit which carries the fluid or to prevent breakage within the pump itself. One of such applications is commonly found in fire equipment wherein the pumper is always supplying fluid 15 under pressure through a hose which has a shut-off valve at the nozzle. This system has several disadvantages, one being the by-pass may clog with the result that the hose is burst, and another being that such apparatus is short lived 20 due to the continuous wear and strain upon the working parts.

Still another adaptation of this old system is presented in the wet nozzle type of gasoline or fuel dispensing systems. In this system, as with 30 the fire apparatus, the fluid is supplied by a pump under pressure through a meter to a nozzle and the flow is controlled by a shut-off valve at the nozzle. When the fluid is not actually being dispensed it is by-passed back into the system. 35 This system entails all of the disadvantages described for the fire equipment. A still further undesirable quality is present in this system. Motor fuels today are of a highly volatile nature and when such a fluid is pumped or recirculated 40 the agitation of the fluid sometimes causes gas formation within the system which may make the system inoperative and which also affects the exactness with which the fluid can be metered. The high pressure also may be damaging 45 to delicate meters.

In the present invention, when applied to fluid displacement pumps, all the foregoing named disadvantages are eliminated. By means of the automatically adjustable wobble plate the fluid 50 flow may be controlled entirely from the nozzle. The system has the advantage therefore of the wet nozzle system without the disadvantages thereof, namely when the fluid flow is retarded or shut off at the nozzle it is not agitated or 55 by-passed. The control of fluid flow is attained

by automatically adjusting the relative angularity of the wobble plate and driven shaft and therefore the stroke of the pistons. This results in no fluid being pumped or recirculated and merely maintains an even steady pressure upon the fluid. 5

In order to more clearly illustrate my invention recourse is had to the accompanying drawings which illustrate an embodiment thereof as applied to a pump particularly adapted for pumping fluid fuels such as gasoline or the like. 10

In the drawings:

Figure 1 is a vertical medial sectional view of the pump showing the position taken by the parts when the fluid is flowing;

Figure 2 is a similar view showing the position 15 taken by the parts when the fluid flow is checked;

Figure 3 is a bottom plan view of the cylinder block; and

Figure 4 is a bottom plan view of the valve 20 used in my invention.

Throughout the figures of the drawings like parts have been designated by like reference characters.

As best shown in Figures 1 and 2, I provide a housing and pump mechanism which may include a cylinder block 1 provided with a plurality of circumferentially disposed cylinders 2 having their axes parallel to each other. The walls of the cylinders are preferably provided with liners 3. The upper end of the cylinders communicate 25 with conduits 4. A cylinder head 5 is disposed on the top of the cylinder block 1 and is provided with a plurality of U shaped conduits 6 which communicate with the conduits 4. Suitable gaskets may be interposed between the cylinder head and the cylinder block, the head being secured to the block by bolts or studs 7. The particular pump shown discloses five cylinders, 30 the number of cylinders may, however, be varied and it is not my intention to limit the same 40 thereby.

The cylinder block is provided with a centrally disposed bore 8, enlarged at the upper end adjacent the cylinder head to provide a valve chamber 9. The lower end of the cylinder block is 45 connected to a crank case 10, a suitable gasket being interposed between the block and the crank case, and the block secured to the crank case by bolts or studs 11.

The crank case has a centrally disposed boss 50 12 in which is cast a journal 13. The passage-way 8 in the cylinder block is counter bored at 16 to provide a seat in which an annular bearing is disposed. The bearing furnishes a support for a driven shaft 20, comprising inner and outer 55

5 races 17 and 18 with interposed balls 19, the inner race of the bearing is disposed upon an annular seat 21 on the driven shaft, and the outer race is held in the seat 16 by upsetting the material of the housing surrounding the seat as at 22. Another bearing is provided for the driven shaft near the bottom of the housing and comprises a similar bearing disposed in a counter bore 23 of the boss 12, a seat 24 being provided 10 on the driven shaft for the inner race. The driven shaft is of reduced diameter at 25 and extends through the journal 13 and through a packing gland comprising a packing 26 disposed in an annular channel in the journal 13 and 15 held in fluid sealing engagement with the shaft and journal 13 by a compression member 27 which is urged against the packing by a thrust spring 28 and adjusting cap 29. The end of the shaft may be connected to a motor, not shown, for 20 rotating the shaft.

25 The portion of the driven shaft intermediate the bearings is adapted to support thereon a wobble plate mechanism. It is provided with an enlarged central portion tapering in each direction as at 31 and 32. The central portion of the tapered shaft is provided with a transverse aperture 33 in which is disposed a pin 34 which extends outwardly on each side of the shaft to provide trunnions which pivotally support a wobble member 35. The tapering portions 31 and 32 of the shaft are of the proper conical formation to provide a seat to limit and predetermine the maximum angularity to which the wobble plate element 35 may be tilted.

35 By thus enlarging the shaft at its point of pivot for the wobble member, the wobble member is held against longitudinal movement on its pivotal axis and a greater degree of tilting of the wobble member may be attained.

40 The wobble element is provided with an annular bearing seat 37 on which is disposed an annular bearing comprising inner and outer races. The edge of the inner race abuts a flange 36 of the wobble element and securely held on the seat and against the flange by a lock nut 38 which is screw threaded on the end of the wobble element. The outer race of the bearing supports a stroke ring 39 of cup shaped formation which seats snugly around the bearing race and is retained thereon by a retaining ring 40 which overlaps the contiguous edges of the wobble plate and outer race and is secured to the stroke ring by 45 screws 51.

55 The stroke ring is provided with a plurality of radial arms 52 in which are disposed connecting rod seat bushings 53. The bushings are locked in apertures in the arms by locking rings 54. The bushings 51 are provided with centrally disposed spherical seats 55. The ends of the connecting rods are provided with balls 56 adapted to rest in the seats and retained therein by the rings 57 which are engaged by the inwardly rolled portions 58 of the seat bushing. A universal joint connection is thus provided for each of the connecting rods 59. The connecting rods extend into the cylinder and are rigidly attached at their other ends to pistons which comprise leather washers 61 and 62 having reversely turned flanges and spaced from each other by a fiber spacer 63. Spring elements 64 are disposed on the upper and lower washers and retain the parts in resilient engagement, all of said elements being centrally apertured and disposed upon a reduced end 65 on the connecting rod and held thereon by a nut 66. A pair of parallel arms 95 extend from the stroke ring and engage a rod

96 embedded in the cylinder block and crank case. The arms are provided with hardened inserts 97 adapted to engage the rod on opposite sides. They prevent the stroke ring from rotating but permit the same to wobble.

5 Means is provided to retain the wobble element seated in an angular position and includes a member 67 disposed upon the drive shaft below the wobble plate and secured immovably to the drive shaft by a set screw 68 and having a radially extending off-set thrust arm 69 which has at its extremity a socket 70. The wobble element 37 carries a corresponding radial lever arm 71 having a socket 72 disposed in alignment with the socket 70. Interposed between the two arms 10 and seated in the sockets is a helical spring 73 which is inserted into the arms under pressure and is adapted to urge the arms away from each other.

15 A valve is provided for controlling the flow of fluid to and from the cylinders and comprises a valve body 75 (Figure 4) having a face 76 adapted to be seated upon a seat 77 in the cylinder head 6 and is adapted to be rotated upon the seat. A channel 78 is provided in the valve 20 and is adapted to connect the conduits 6 with exhaust passage 79. The exhaust passage may be threaded to receive a suitable coupling for connection to a delivery hose, not shown. An inlet port 80 is provided through the valve for 25 admitting fluid from the valve chamber to the conduits 6.

30 An eccentrically disposed downwardly extending boss 81 is provided on the valve. The boss is bored at 82 on the axial center of the valve 35 to receive the end of the driven shaft. A transverse slot 83 extends through the boss 81 and bore 82 and the driven shaft carries a pin 84 adapted to extend transversely of the shaft into said slot adapted to provide a driving connection 40 between the shaft and valve. The end of the boss 81 terminates in a slanting surface 85 slanting toward the greatest radius of the eccentric and merging with a flat thrust surface 86. Resilient means is provided to hold the valve seated 45 and includes a lower thrust collar 87 surrounding the driven shaft and bearing against the edge of the inner bearing race 17. The collar is eccentrically disposed on the shaft and is provided with a radially extending spring seat 88. A helical spring 89 is disposed about the driven shaft 50 and rests on the seat 88. A substantially similar collar 90 is disposed slidably upon the driven shaft and is engaged by the other end of the spring 89. A drive pin 91 is pressed into an aperture in the collar 90 parallel to the driven shaft axis and has a head which extends into and engages the sides of the slot 83 of the boss 81 to provide a positive drive between the thrust collar and valve, the valve and thrust collars are eccentrically aligned relative to the shaft so that the thrust of the collar is applied to the valve at the eccentric portion of the boss on the valve. An inlet 93 is provided in the crank case 10 adapted to be coupled to an inlet conduit which is connected to a storage tank or the like, not 55 shown. Inlet passages 98 are provided through the cylinder block to permit fluid to flow to the valve chamber 9. Suitable mounting means 100 may be provided on the crank case.

60 It being understood that the inlet 93 is connected to a gasoline storage tank or the like, not shown, the mechanism being in a position as shown in Figure 1, the driven shaft is rotated by a motor. Inasmuch as there is yet no pressure 65 within the apparatus, the spring 73 between the 75

arms 69 and 71 rotates the wobble member about its transverse axis upon the trunnions of the pin 34 until the bore of the wobble member is seated upon seats 31 and 32 of the driven shaft. The 5 spring 73 thus retains the wobble member in this predetermined angular position. Rotation of the driven shaft rotates the wobble member which imparts a wobbling motion to the stroke ring, the stroke ring being held against rotation. The 10 wobbling motion of the stroke ring is communicated to the pistons through the connecting rods 59, imparting reciprocating motion to the piston within the cylinders. A piston being at the top of the cylinder, the inlet port 80 will be aligned 15 with the conduit 6. As the piston goes down into the cylinder, fluid will be drawn through the inlet 93 into the crank case through the ducts 98 into the valve chamber and through the inlet port 80, conduit 6, and passage 4 into the cylinder. When 20 the piston reaches the bottom of the cylinder the valve which has been rotated by the drive shaft now has rotated to a point wherein the inlet opening is closed and the exhaust channel 78 registers with the conduit 6 as shown in the Figures 1 25 and 2. On the up-stroke of the piston the fluid is expelled through the conduits 4, 6, and channel 78 in the valve and out the outlet 79. This cycle of operation is continuous for all five cylinders as long as the pump is pumping. Should the fluid 30 flow be retarded by shutting a valve on the end of a nozzle which is connected by a conduit to the exhaust 79 the fluid pressure within the pump will immediately build up. As the pressure in the pump increases the pistons on the exhaust stroke 35 are unable to expell the fluid from the cylinders and the pressure therefore prevents them from rising in the cylinder. The movement of the wobble plate continuing and the piston being unable to move, the pressure is placed upon the 40 wobble plate through the connecting rods which causes the angularity of the wobble plate to change because of the resiliency of the spring 73 between the arms 69 and 71 which compresses and permits the wobble element to rotate on its trans- 45 verse axis 34 until it attains a position as best shown in Figure 2. In this position it can be seen that the drive shaft can still rotate but that no wobbling of the wobble plate occurs because the plane of the wobble plate is at right angles to the shaft axis. In this position although the wobble member 35 rotates there is no wobbling movement and therefore no reciprocating motion applied to the piston, until the pressure above the pistons becomes less than the pressure necessary to overcome 50 the compression moment of the spring 73. This does not occur until the valve at the nozzle is released permitting fluid to again flow at which time the pressure above the piston becomes less and the wobble plate is released and urged back 55 to its normal angular operating position as shown in Figure 1.

It will thus be seen that the volumetric flow of fluid in the pump is entirely dependent on the pressure above the pistons; that there is no agitation of the gasoline due to recirculatory action such as would cause the volatile fluid to volatilize or form gaseous pockets or the like nor is there any necessity of any by-pass. It will also be seen that during the high pressure periods there is no reciprocation of the pistons in the cylinder and therefore the wear of the mechanism is reduced to a minimum.

It is to be noted that the fluid from the conduit 6 is directed into the exhaust channel 78 of the valve in such a manner that under ordinary cir-

cumstances it tends to exert a pressure on the valve urging the valve away from its seat. This pressure is not an equal pressure downward on the entire valve, but is a one-sided pressure due to the location of the channel 78 in the valve and the conduit 6 above the valve. There is therefore a tendency of the valve to wear more on one side of the face than on the other and this is undesirable. In the present invention this is overcome because of the manner in which the thrust, which urges 10 the valve towards the seat, is applied. As described previously, the spring exerts a pressure on the valve eccentric to the valve axis. This is so positioned as to apply the spring pressure to the valve opposite the place where the greatest fluid 15 load is upon the valve, hence balancing the valve against such load.

Although the drawings have illustrated the pump as being in a vertical position for the purpose of the description, it is to be understood that 20 the pump can be disposed in any position; and, although I have described the invention as applied to a gasoline pump, it is also understood that it is not limited to its use thereby but may be used to replace any kind of a pump where varying volumetric displacement is desirable or where a pumping safety factor is desired. The mechanism will operate with any number of cylinders but will always operate on the same principle.

Having thus described an embodiment of my invention and an application of its use I am aware that numerous and extensive departures may be made from the embodiment shown without departing from the spirit and scope of the invention which is defined by the appended claims.

I claim:

1. In a valvular mechanism for a fluid meter or pump of the wobble plate type including a housing, a driven shaft, a plurality of cylinders, pistons for the cylinders and a wobble plate for the shaft and adapted to impart reciprocating motion to the pistons, said housing formed to provide a valve chamber with channels from the cylinders to the valve chamber and a seat in said chamber, said channels opening through said seat, a rotary valve in said chamber and adapted to seat upon the seat, means to rotate said valve upon the seat including a connection between the driven shaft and the valve, means to thrust the valve against the seat including a spring eccentrically disposed 45 relative to said driven shaft adapted to exert a pressure upon the valve at the point opposed to the greatest fluid pressure upon the valve.

2. In a valvular mechanism for a fluid meter or pump of the wobble plate type including a housing, a driven shaft, a plurality of cylinders, pistons for the cylinders and a wobble plate for the shaft and adapted to impart reciprocating motion to the pistons, said housing formed to provide a valve chamber with channels from the cylinders to the valve chamber, and a seat in said chamber, said channels opening through said seat, a rotary valve in said chamber and adapted to seat upon the seat, means to rotate said valve upon the seat including a connection between the driven shaft and the valve, means to hold the valve resiliently pressed against said seat to overcome fluid pressure against the valve including a spring eccentrically disposed about the driven shaft and adapted to exert a pressure upon the 60 valve at a point in opposition to where the greatest fluid pressure is exerted by fluid against the valve.

3. In a fluid pump, a housing, cylinders in the housing, pistons in the cylinders, a shaft, means 75

- connected to the shaft and the pistons to reciprocate the pistons in the cylinders, said housing formed to provide fluid conduits communicating with said cylinders and a valve chamber
- 5 having a valve seat, said conduits opening through said seat, a valve for controlling fluid flow through said conduits, means to hold said valve seated upon the seat including a spring, eccentric thrust members engaged by the spring
- 10 and adapted to exert pressure against the valve in a direction opposing the fluid pressure upon the valve.
4. In a fluid pump, a housing, cylinders in the housing, pistons in the cylinders, a driven shaft, a wobble member secured to the driven shaft, a stroke ring carried by the wobble member and operatively connected to the pistons to reciprocate the pistons, said housing formed to provide an inlet, an outlet, and a valve chamber
- 15 with conduits communicating between the cylinders and the valve chamber, a seat in said valve chamber, said conduits and said outlet opening through said seat, said inlets communicating with said valve chamber, means to control fluid flow through the pump including a valve disposed in the valve chamber and seated on said seat, said valve formed to provide an outlet duct and an inlet duct, said outlet and inlet ducts adapted for registering alternately with said conduits, a boss upon said valve provided with an axial recess adapted to receive the end of the driven shaft, an eccentrically disposed shoulder on said boss, means to retain said valve resiliently seated on said seat including, a pair of eccentric thrust members disposed on said shaft, a helical spring disposed between said thrust members, one of said members being held connected in interlocking engagement with the eccentric bosses on said valve, said means being
- 20 adapted to exert a pressure on the valve spaced from the axial center of the valve at a point opposite to where greatest fluid pressure is exerted on the valve to balance the valve against said fluid pressure.
- 45 5. In a fluid pump, a housing, cylinders in the housing, pistons in the cylinders, a driven shaft, a wobble member secured to the driven shaft, a stroke ring carried by the wobble member and operatively connected to the pistons to reciprocate the pistons, spring means for varying the angularity of the wobble member to vary the amount of reciprocation of said piston, said housing formed to provide an inlet, an outlet and a valve chamber with conduits communicating between the cylinders and the valve chamber, a seat in said valve chamber, said conduits and said outlet opening through said seat, said inlets communicating with said valve chamber, means to control fluid flow through the pump including a valve disposed in the valve chamber and seated on said seat, said valve formed to provide an outlet duct and an inlet duct, said outlet and inlet ducts adapted for registering alternately with said conduits, a boss upon said valve, an axial recess, said driven shaft being keyed to said valve in said axial recess, an eccentrically disposed shoulder on said boss, means to retain said valve resiliently seated on said seat including, a pair of eccentric thrust members disposed on said shaft, a helical spring disposed between said thrust members, one of said members being held connected in interlocking engagement with the eccentric boss on said valve, said means being
- 50 75 adapted to exert a pressure on the valve spaced from the axial center of the valve at a point opposite to where greatest fluid pressure is exerted on the valve to balance the valve against said fluid pressure.
- 5 having a variable displacement fluid pump, a housing, a plurality of cylinders in the housing, pistons reciprocably disposed in the cylinders, means to reciprocate the pistons in the cylinders including a driven shaft rotatably journaled in the housing, a wobble member transversely pivoted on and rotatable with said driven shaft, a lever arm carried by said wobble member, a thrust arm carried by the driven shaft, spring means supported between said arms and adapted to urge the arms away from each other to tilt the wobble member about its transverse pivot, said driven shaft formed to provide a seat about which the wobble member is disposed and adapted to limit and predetermine the maximum amount of tilting of said wobble member, a stroke ring carried by said wobble member, said wobble member being rotatable relative to the stroke ring, means to prevent rotation of the stroke ring, and means connecting the stroke ring to said pistons; said housing being formed to provide a valve chamber having a valve seat, conduits connecting said cylinders to said valve chamber and opening through said valve seat, an outlet opening into said valve chamber through said valve seat, an inlet with ducts communicating with said valve chamber; a valve disposed in said chamber and adapted to be held against said valve seat for controlling flow of fluid from the valve chamber to the cylinders and from the cylinders to the outlet, said valve formed to provide an exhaust channel in the valve and an intake port through the valve, said channel and said port adapted to be alternately registered with said conduits, said exhaust channel being in continuous registry with the exhaust opening; an eccentric boss carried by said valve having a recess axially disposed relative to the body of the valve and adapted to receive the end of the driven shaft and means connecting the driven shaft in driving relation to the valve; means to hold the valve resiliently pressed against its seat including an eccentric thrust member carried by the driven shaft, a second thrust member slidably disposed on the shaft, said second thrust member being adapted to contact with the eccentric boss on said valve at the greatest point of eccentricity of said boss and rotatable therewith, a spring disposed about the driven shaft and engaging said thrust members to thrust said second thrust member against said valve boss to urge the valve against the seat, the point of application of pressure against said valve being such as to balance the valve against the pressure of fluid in said exhaust channel in said valve.
7. In a fluid pump, a housing, cylinders in the housing, pistons in the cylinders, a driven shaft, a wobble member secured to the driven shaft, a stroke ring carried by the wobble member secured to the driven shaft, a stroke ring carried by the wobble member and operatively connected to the pistons to reciprocate the pistons, said housing formed to provide an inlet, an outlet, and a valve chamber with conduits communicating between the cylinders and the valve chamber, a seat in said valve chamber, said conduits and said outlet opening through said seat, said inlets communicating with said valve chamber, means to control fluid flow through the pump including a valve disposed in the valve chamber and seated

- on said seat, said valve formed to provide an outlet duct and an inlet duct, said outlet and inlet ducts adapted for registering alternately with said conduits, a boss upon said valve provided 5 with an axial recess for the end of the shaft, said boss provided with an inclined surface, means to retain said valve resiliently seated against the seat comprising, a pair of thrust members disposed about said shaft, and a spring engaging 10 the thrust members to hold one member against the highest portion of the inclined face of the boss on the valve adapted to exert pressure on the valve at a point opposite to the greatest fluid pressure on the valve.
- 15 8. In a fluid pump, a housing, cylinders in the housing, pistons in the cylinders, a driven shaft, a wobble member pivotally secured to the driven shaft, a stroke ring carried by the wobble member and operatively connected to the pistons to reciprocate the pistons, means to hold the wobble member at a predetermined angular position and to permit the angular position to be varied upon application or predetermined pressure to the pistons, said housing formed to provide an inlet.
- 20 an outlet, and a valve chamber with conduits communicating between the cylinders and the valve chamber, a seat in said valve chamber, said conduits and said outlet opening through said seat, said inlets communicating with said valve chamber, means to control fluid flow through the pump including a valve disposed in the valve chamber and seated on said seat, said valve formed to provide an outlet duct and an inlet duct, said outlet and inlet ducts adapted for registering alternately with said conduits, a boss upon said valve provided with an axial recess for the end of the shaft, said boss provided with an inclined surface, means to retain said valve resiliently seated against the seat comprising, 5 a pair of thrust members disposed about said shaft, and a spring engaging the thrust members to hold one member against the highest portion of the inclined face of the boss on the valve adapted to exert pressure on the valve at a point opposite to the greatest fluid pressure on the valve.

FERDINAND E. FICK.
